UNITED STATES PATENT OFFICE.

CHARLES H. EYER, OF WEST NEW YORK, NEW JERSEY.

OIL-PRESSURE FEEDING DEVICE.

Application filed August 8, 1926. Serial No. 126,827.

This invention relates to lubricating systems as applied to gasoline engines and more particularly to such as are installed in self-propelled vehicles of the automobile 5 type.

Such engines are invariably of the multi-cylinder class having a crank shaft disposed in a horizontal plane, its several cranks dipping into an oil chamber in the 10 lower crank case at each revolution, in timed relation, to pick up a small quantity of oil and by a series of splashes provide lubrication to the cylinders and bearings.

This system works well in theory and also 15 in practice during the time when a copious supply of fresh, clean oil is supplied to the chamber and the car is operated over a substantially level surface.

Eventually however the oil becomes 20 thickened by accumulation of foreign particles, due to wear and abrasion of parts, entry of extraneous matter and the like, not infrequently of such nature as to clog the inlet, and on the other hand occasionally 25 the oil becomes diluted by mixture with gasoline from leaky connections, in either case reducing the functional value of the oil as a lubricant or destroying it altogether.

It is also well known that as liquids seek 30 to maintain their level, the oil will flow by gravity to the lowest part of the chamber when the vehicle is inclined, as in going up or down a hill, thus depriving certain of the cranks and cylinders from receiving 35 their proper and proportional share of lubrication to their detriment, causing excessive wear, heating, noise and ultimate ruin.

Probably no other assemblage of mechanism 40 is operated under conditions which are so much to its disadvantage as a motor car or where the necessity of ample and automatic lubrication is more urgent.

It is therefore one object of the present 45 invention to provide means for causing a positive circulation of oil through the crank case and transmission chambers, entering the same at the front, rather than at the rear as is usual, so that in hill climbing the forward cylinders as well as the rear are 50 effectively lubricated.

A further feature is in the provision of means for supplying a constant stream of oil under pressure through the breather pipe

to the timing gears and crank case and also directly to the transmission case at a point 55 above the several bands therein.

Another advantage is in supplying an oil pressure gage, preferably on the dash board, where it can be readily seen by the operator, this gage indicating the condition of 60 the oil, if thinned or reduced by gasoline, the pressure under which it is supplied, and also if the supply be exhausted or cut off.

Finally it is proposed to furnish the device by which the system is operated in the 65 form of an attachment applicable to old as well as new motor cars by the substitution of a single new part, requiring no machining or refitting, together with the placement of a gage and simple pipe connections.

These several valuable and practical features are accomplished by the novel construction and arrangement of simple parts 75 hereinafter described and shown in the accompanying drawings, forming a material portion of this disclosure, and in which:—

Figure 1 is a general side elevational view showing a complete operating system 80 as installed in a Ford motor car, the showing being largely diagrammatic.

Figure 2 is a side view of the timing case and oil pressure pump attachment.

Figure 3 is a front elevational view of the same with the pump casing cover removed.

Figure 4 is a transverse sectional view taken on line 4—4 of Figure 5.

Figure 5 is a sectional view taken on line 5—5 of Figure 4.

In Figure 1 is a diagrammatically shown a transmission case 10, supplied with a removable cover 11, the case being expanded towards the front as at 12 to enclose a fly wheel, magneto and planetary gears (not 95 shown).

This case is formed with upper and lower sections which further extend to constitute a lower crank case 13 reaching toward the front and an engine block or housing 14 100 thereover, bolted together in a horizontal plane along the flanges 15 which are substantially level with the axis of the crank shaft.

Bolted within the front end of the upper 105 portion of the crank casing is a generator

and timing gear case, these elements all being of the usual standard type of construction.

In the present embodiment a new gear case 16 is substituted for that originally installed, the same being secured by the original bolts in the same openings in the casing.

Enclosed in the casing, which has a cover 17, is a spur pinion 18 in mesh with the cam or timing gear 19 driven by a pinion of half its size fixed on the outer portion of the crank shaft, the pinion 18 also meshing with a smaller pinion 20 fixed on a spindle 21 housed in the upper part of the case and extending outwardly towards the front through a stuffing box 22.

Rigidly bolted to the cover plate 17 is an offset outstanding bracket 23 supporting an oil pump casing 24 into which the spindle 21 enters through a stuffing box 25.

The squared end of the spindle 21 has fixed on it a toothed wheel 26 meshing with a mating wheel 27 rotatable on a stud 28 set 25 in the body of the casing which is provided with a cover plate 29 held removably by screws as shown, the ensemble constituting a common form of rotary pump.

In the side of the casing 24 is an opening 30 for priming the pump when initially started, the same being normally closed by a plug 30.

The casing has the shape of a flattened ellipse disposed at an angle to its support and at its upper end is a raised projection 31 containing a pair of threaded inlet and outlet openings respectively 32 and 33 communicating with ports 34 and 35 disposed in the casing midway between and at the sides of the chambers in which the toothed 40 rotors 26 and 27 revolve, it being understood that the points of the wheel teeth merely clear the walls of their chambers.

The inlet opening 32 is connected by a nipple and union with a pipe 36 leading to 45 similar connections communicating with a hollow annulus 37 fixed on a tubular plug entering the drain opening in the casing outlet 12' to receive oil as collected therein.

The outlet opening 33 is connected with a 50 T fitting 38 one branch of which has engaged in it a pipe 40 communicating with an open-

ing through the cover plate 11 to supply oil to the mechanism in the casing 10, and a branch 40' of the pipe leads downward through the breather pipe to supply the timing gears and dippers with a constant current of oil.

The other branch of the T 38 is connected with a pipe 42 leading to an oil pressure gage 43 set in the vehicle dash board 44 whereby 60 the pressure in the oil system by the pump can at any time be seen, such pressure being preferably maintained at approximately eight pounds per square inch.

Should the pump fail to properly operate 65 from any cause, as clogging of the pipes, or insufficient supply, this fact is at once apparent; also in case of the oil becoming diluted or thinned, the pressure obviously 70 will fall, calling attention to the fact that proper lubrication is not being supplied.

It will be clear that a suitable oil stream 75 will be provided whenever the motor is operating and that the same is entirely independent of any inclined position that the car may assume.

As changes of construction could be made within the scope of the invention, it is intended that all matter contained in the foregoing description or shown in the accompanying drawings shall be interpreted as 80 illustrative and not in a limiting sense.

Having thus described my invention, what I claim as new and desire to secure by Letters Patent, is:—

In an oil feeding system for a motor car of the planetary gear type, in combination with a generator gear, a rotary pump, and an auxiliary gear rigidly mounted upon a shaft connected with the pump gears, said auxiliary gear being in mesh with the generator gear, so that whenever the motor is running the pump will operate, and a casing for the auxiliary gear and the generator gear, said casing having holes coinciding with the bolt holes in the standard crank case, a cover for said casing, and a bracket mounted on said cover to support the pump.

Signed at New York, in the county of New York and State of New York, this 29th day of July, A. D. 1926.

CHARLES H. EYER.
